DUPLEX REGISTER CALCULATING MACHINE

Grant C. Ellerbeck, San Leandro, Calif., assignor
to Friden Calculating Machine Co., Inc., a cor-
poration of California

Application January 30, 1950, Serial No. 141,223

12 Claims. (Cl. 235—79)

1

The present invention relates to calculating machines and has as its general object the provision of a mechanism by means of which the counter of a rotary type calculating machine can be selectively used as a grand totalizer.

It is a primary object of my invention to provide an improved form of duplex accumulators in which the normal counter can be used selectively as a grand totalizer, the counting mechanism being rendered inoperative during such operation.

Another important object of the invention is to provide a mechanism by means of which a counter register utilizing a planetary, or crawl type, tens-transfer, can be connected to the accumulator register, whereby both the counter and the accumulator can be operated from the actuator in unison to in effect, provide a machine with two accumulators, either one of which can be cleared from time to time while maintaining grand totals to be accumulated in the other.

Another important object of my invention is to provide a mechanism which is selectively settable to render the counter and register of the type best shown and described in the patent to Avery, No. 2,211,736, into a duplex accumulator calculating machine.

These and other important objects of my invention will be readily understood from the description and claims which follow. A preferred form of my invention is shown in the accompanying drawings in which:

Fig. 1 is a cross-sectional view of the carriage of a calculator of the type shown in said patent, taken on a plane to the right of the first order of the register and showing the mechanism of my invention, as well as the accumulator drive, in a disengaged position.

Fig. 2 is also a cross-sectional view of the carriage, but is taken on a plane to the right of one of the intermediate orders of the register (such as the plane indicated by the line 2—2 of Fig. 5) and shows the "dipping carriage" dipped to engage the actuator with the accumulator, but with the connecting mechanism of my invention in a disengaged, or normal, position.

Fig. 3 is similar to Fig. 2 but shows the connecting mechanism of my invention in operative position to actuate the "counter" register from the actuator in unison with the accumulator register.

Fig. 4 is a left-end view of the calculator carriage, with cover and all other parts removed which are not necessary to an understanding of my invention.

Fig. 5 is a plan view of the mechanism of my invention.

Fig. 6 is a front view of two orders of the accumulator register showing the preferred type of planetary, or crawl, tens transfer.

A preferred utilization of my invention is to convert the calculator of the above-mentioned

2

patent into a truly duplex accumulator machine, in which the normal counting mechanism can be rendered inoperative and the counter register used as a grand totalizer. For purposes of simplification the machine of that patent is not described in detail as most of the parts of the machine are not concerned with the operation of my invention. In order to render my invention more readily apparent to those familiar with the machine of said patent, I have used the same reference characters as used in the patent, when the parts are the same as shown in the patent. However, when the parts have been slightly modified this fact is shown by adding another digit to the reference character used in the patent, e. g., the shaft 262 of the patent is changed to 2620 as I prefer that the shaft be splined, as shown, instead of cylindrical as in the patent. The new parts added by my invention are shown by reference characters ranging between 2000 and 2100.

Values are entered into the register by means of a gear 189 (Figs. 1 to 3, inclusive) which is keyed to a collar 169 rotatably mounted on the shaft 170. The amount of rotation of the gear 189 is determined by the position of selection plates, such as 172, which serve to connect the gear 189 through one of a number of gear trains with a predetermined drive shaft, not shown herein but fully shown and described in said patent.

The accumulator and the counter mechanisms are mounted in a carriage which is shiftable transversely across the machine. The carriage frame comprises end plates 251 (Fig. 4) rigidly connected by a stop plate, not shown, and the various cross shafts some of which will be hereafter mentioned. The carriage is shiftable on the carriage track shafts 259 and 260. Mounted at even intervals between the end plates 251 are a series of carriage brace plates 255 (Figs. 1, 2 and 3) which are locked to the stop plate, not shown. Locked spacing combs 263 extend through spaced slots in each brace plate, holding them in rigid spaced relationship. A cross shaft 2620 is mounted in the front end of the brace plates 255, and supports the front end of the "dipping carriage." The "dipping carriage" comprises the plates 266 pivotally mounted on shaft 2620, which plates are locked in rigid relationship by means of a comb 267 and a common "dipping bail" 269. Normally the "dipping carriage" is in the raised position shown in Fig. 1. At the beginning of a cycle of digitation the "dipping carriage" is lowered by means of the bail 269 into the position shown in Figs. 2 and 3 in which the gearing of the accumulator mechanism engages the actuator gears 189, as shown in these figures.

The dipping of the "dipping carriage" is controlled, as shown in Fig. 4, by means of a link 566 which is provided with a pair of rollers 568 em-

bracing the common bail 269. The link 566 is mounted on a suitable pin 567. Movement of the link 566 is controlled by means of a lever 601 the bifurcated end of which embraces a pin 602 on the link 566, all as explained in the aforementioned patent.

The various ordinal units of the accumulator are mounted on a common shaft 270 carried by the various plates 266 of the "dipping carriage." In each order the accumulator mechanism includes a drive gear 273 rotatably mounted on a collar 293 supported by the shaft 270. This gear in turn is driven by an idler gear 271 rotatably mounted on shaft 272, also supported in the "dipping carriage," the idler gear meshing with the actuator gear 189 when the carriage is in the dipped position. Associated with the accumulator mechanism is a suitable detent 319 in each order suitably mounted on shaft 320, likewise journalled in the "dipping carriage." Normally, the nose of the detent engages the teeth of the idler gear 271, but as the carriage is dipped for digitation, the lower arm of the detent engages the cross shaft 555 to rock the detent clockwise and thus disengage it from the idler gear. The detent is normally pulled in a counter-clockwise direction by a suitable spring 3170.

It will be understood, of course, that the accumulator mechanism includes the customary dials and a suitable tens-carry mechanism preferably of the type shown and described in said patent, and shown in part in Fig. 6 hereof. Although such elements are not a part of my invention, a suitable tens carry mechanism is necessary to the proper operation of my invention and will therefore be briefly described. Two units, or orders, of the preferred form of register are shown in Fig. 6. It is preferred that the accumulators and the counters be identical and that they utilize the same preferred type of tens-transfer mechanism. Therefore, one order only of the accumulator will be described, but it will be understood that the counter is substantially the same.

It will be noted in Fig. 6 that each ordinal unit comprises a spider 274 which is rigidly secured to a sleeve 275 on shaft 270. This spider 274 carries an internal ring gear 276. One of the arms of the spider carries an angular extension 278, which extends slightly beyond the right side face of a thin shell 279 fixed to the spider 274 and serves as a zero stop in resetting operations. The periphery of the shell 279 is sufficiently wide to accommodate the digits ranging from 0 to 9 arranged as shown.

Integral with the sleeve 275 on shaft 270 is a sun gear 280 abutting one of the brace plates 266 and interposed between said sun gear 280 and the spider 274 is a snail cam 281 and spacer 282. A projection 283 from the spider extends into an enlarged slot, not shown, in the cam to permit limited movement of said cam with respect to the spider.

Located immediately to the right of the mechanism just described is a plate 292 fixed to a spur gear 273 which is driven by the actuator gear 189 through an intermediate or idler gear 271 when the plates 266 are dipped. These elements are rotatably mounted on a sleeve 293 which in turn is rotatably mounted on a sleeve 294. Plate 292 is in turn fixed to a plate 295 by studs 297 provided at each end of said plate, and on each of said studs is mounted a planet gear 298 meshing with the ring gear 276 carried

by spider 274 and with another sun gear 299 formed integrally with sleeve 293. Thus, the spur gear 273, the plate 292, the planet gears 298, and the ring gear 276 constitute a planetary assembly which rotates about the sun gear 299 and comprises the means by which the numeral bearing shell 279 can be rotated by the actuating mechanism of the machine which drives the gear 271 as hereinbefore described.

Means are provided for driving the spider 274 and its associated dial shell 279 by means of the spider 274 of the next lower order independently of any movement of gear 273. This means includes a spider 300 secured to the right end of the above-mentioned sun gear sleeve 293 which spider carries an internal gear 301. Sleeve 294 which, as previously described, supports the sleeve 293 on shaft 270 is provided with a double arm member 304, one arm 306 of which supports a stub shaft 307 to which are fixed planet gears 308 and 309. The planet gear 308 meshes with the internal gear 301 on spider 300 while the planet gear 309 meshes with the sun gear 299 of the adjacent lower order. Sleeve 294 also includes an integral spacer 310 so that the gear 308 is positioned in alignment with the ring gear 301 and does not abut the spider 300.

The member 304 is rocked, as is fully described in the above-mentioned patent, by a lever, not shown, which is positioned by a lever 315 which carries roller 316 in the same plane as the snail cam 281 of the next lower order. This construction permits the amount of movement of the dial 279 imparted to it by tens-carry from the next lower order to be backed off by the snail cam, as fully described in said patent.

For the present invention it suffices to point out that in operation the gear 273 is driven by the actuating mechanism and revolves planetary gears 298 about shaft 270 as a center. Whenever a given amount is thus entered in any one unit of the accumulator, member 304 being held in fixed position, one-tenth of that amount will be entered in the next higher unit by means of the carrying mechanism comprising sun gear 280 fixed to spider 274 and driving planetary gears 308 and 309. These in turn drive integral gear 301 fixed to sleeve 293 of the next higher unit in a direction opposite to that of spider 274 and, by rotating said sleeve, drives sun gear 299 integral therewith. If gear 273 and studs 297 are stationary, the movement of sun gear rotates ring gear 276 in the direction opposite to that of gear 299 and therefore in the same direction as that of the lower order dial transmitting the carrying. If gear 273 is moving to introduce digitation as previously described, ring gear 276 will move by an amount equal to the resultant of that produced by the rotation of both gear 299 and gear 273. Thus, the movement of any higher order dial becomes the resultant of the digitation entry into its own order and the carry movement from the next lower order, as is more fully described in said patent.

In some machines of this type the counter extends over approximately half of the carriage, but it is preferred that the counter or counters, extend the full width of the carriage in my invention, as is shown in the patent above referred to. It is immaterial whether the counter is a single counter extending the full length of the carriage or whether it is the duplex counter described in said patent. In either event the operation of my invention will be the same. The counter register comprises a plurality of dials,

not shown, each of which is connected to a driving gear 1879 rotatably mounted on a cross shaft 1876 journaled in the brace plates 255 of the carriage. The dials, tens-carry mechanism, and associated mechanisms are similar to those of the accumulator and need not be described again. The gear 1879 is driven by an idler gear 1877 mounted on a cross shaft 1878, also mounted in the brace plates 255 of the carriage. The idler gear 1877 in turn is driven by the counter gear 1880 rotatably mounted on cross shaft 1921. A suitable detent 1932 normally engages the idler gear 1877, being pulled counter-clockwise by a suitable spring 18850.

The counter gears 1880 are mounted in the carriage and are driven by a single counter actuator 1824 (Figs. 4 and 5), the nose 18240 of which moves the gear 1880 a single space for each cycle of the machine, as described in said patent. As shown in Fig. 4, the counter actuator 1824 is pivotally mounted on a lever 1830 which is actuated by an eccentric, not shown, to move the nose 18240 into engagement with the counter gear 1880, then upwardly or downwardly as the case may be (depending upon whether digitation is positive or negative), and then to retract the nose to an inoperative position. The forward end of the counter actuator 1824 is supported on a pin 1831 carried by bar 18310. The actuator 1824 is provided with a suitable slot 18311 which embraces the pin 1831. In the patent above-mentioned the actuator 1824 is pinned to the actuating lever 1830, as there is no occasion when the counter will be rendered inoperative. In my invention, however, it is necessary that the counter be rendered inoperative when the counter register is utilized as a grand totalizer. It is therefore necessary in my invention to provide a yieldable connection between the actuator lever 1830 and the counter actuator 1824. This can be accomplished by means of a suitable slot 18241 which embraces the pin 18242 carried by the actuator lever 1830. A suitable spring, such as torsion spring 2075, tends to hold the actuator 1824 in its extended position, but to permit the actuator to remain stationary when an ear 2070 is interposed in front of the nose 18240. Thus the actuator 1824 can be blocked from operating the counter gear 1880 although the actuator lever 1830 rocks as in ordinary operation.

The mechanism heretofore described is conventional as will be shown by a reference to said patent. My invention relates to a mechanism by means of which it is possible to selectively connect the accumulator gearing to the counter gearing so that the counter is rotated in step with the accumulator while simultaneously disengaging the counter actuator 1824 from the counter gear 1880. Thus, a value entered into the accumulator is entered simultaneously into the counter. As the accumulator can be cleared without clearing the counter, my mechanism enables the conventional counter to be used selectively as a grand totalizer or as a counter. The mechanisms by means of which these results are secured will now be described.

My invention comprises interposable gears 2000 which can be positioned selectively between the accumulator gears 273 and the counter gears 1879. A preferred form of my invention is shown in the drawings and especially in Figs. 1, 2 and 3. The mechanism is identical in the several orders of the machine, so only the structure of one order need be described. Preferably the interposable

gear 2000 is rotatably mounted on a stud 2001 carried by a rocker arm 2002 which is pivotally mounted on shaft 270. It will be understood that a single shaft suitably supported against flexing could be substituted for the several studs 2001. The lower end of the rocker arm 2002 is provided with a slot 2003 which embraces the shaft 2620 and permits the rocker arm 2002 to be rocked slightly about its pivot point 270. The lower end of the rocker is also provided with a camming surface 2004 with which is associated an ear 2011 hereinafter described. The rocker arm 2002 is normally pulled to its extreme counter-clockwise position by means of a spring 2006 tensioned between a pin 2005 on the rocker arm and a pin 2007 carried by the plate 260. A pin 2008 on the spacing plate 255 limits the counter-clockwise rocking of the rocker arm 2002.

The ears 2011 above-mentioned are mounted on levers 2010, keyed to spline shaft 2620. It will be understood that in the embodiment illustrated in the drawings there is one such lever 2010 for each order of the register. However, a single bail suitably supported against flexing could be used in place of the several levers shown, as is evident to those skilled in the art. In the form shown, the levers 2010 are suitably spaced from the brace plates by spacers, not shown. An arm 2013 is keyed to the left end of shaft 2620, as shown in Fig. 4. The arm 2013 is pivotally connected to a link 2015 by any suitable means, such as pin 2016.

A control lever 2020 (Figs. 4 and 5) is pivotally mounted on the left end plate 251, by any suitable means such as large-headed screw 2021. The free end of the link 2015 is pinned to the control lever 2020 by any suitable means, such as pin 2022.

The control lever 2020 is also provided with a suitable stud 2023 which cooperates with the nose 40 of a centralizer arm 2024. The centralizer is pulled in a counter-clockwise direction, as shown in Fig. 4, by a suitable spring 2025 tensioned between the centralizer arm 2024 and a stud 2626 riveted on the end plate 251.

Preferably, the lower end of the control lever 45 2020 is provided with a slot 2030 having two substantially perpendicular extensions 2031 and 2032 which embrace the tit 3200 on the end of shaft 320 when the "dipping carriage" is lowered into its dipped position at the beginning of a digitation cycle. It is obvious that when the tit 3200 is lowered into either of these perpendicular slots 50 operation of the control lever 2020 is effectively prevented. Thus changing the position of the control lever is impossible during digitation.

The control lever 2020 is positioned forwardly (rocked clockwise as in Fig. 4) to position the bail 2011 forwardly of the camming surface 2004 as is shown in Fig. 2. In this position the gear 2000 60 being in mesh with gear 273, will of course rotate therewith. However, the spring 2006 will rock the rocker arm 2002 counter-clockwise so that even on depression of the "dipping carriage" the interposable gear 2000 will not become enmeshed with gear 1879. This position is shown in Fig. 2. When the control lever 2020 is pushed to its rearward position (counter-clockwise of that shown in Fig. 4), the bail 2011 is rocked rearwardly to the positions shown in Figs. 1 and 3. In this position the bail 2011 has engaged the camming surface 2004 and rocked the rocker arm 2002 clockwise. In this position the interposable gear 2000 65 is not engaged with the gear 1879 when the "dipping carriage" is in its uppermost, or normal, position. Therefore, when the machine is set for

accumulating operation, the two registers are not connected except during digitation, and either register can be cleared without effecting the other. However, when the "dipping carriage" is lowered to engage the idler gear 271 with the actuator gear 189, the interposable gear 2000 is rocked into engagement with the counter gear 1879 so that (assuming that the counter actuator is rendered inoperative) the counter gear 1879 will rotate in unison with the accumulator gear 273. Thus, values transmitted from the actuator gear 189 are entered simultaneously into the accumulator and the counter, through the gears 273 and 1879, respectively.

It might be mentioned at this point that the 15 rocking of the interposable gear 2000 into engagement with the counter gear 1879 will normally cause that gear to rotate slightly to momentarily give an incorrect reading of the counter register. However, in high-speed machines of the type described, the dials are normally rocked at the beginning of digitation through the release of the partial value blockout of the crawl tens-transfer mechanism, and are immediately followed by rotation resulting from digitation, so that this slight movement of counter gear 1879 is not objectionable. It will be understood, further, that upon disengagement of the interposable gear 2000 from the counter gear 1879, which occurs at the end of each cycle of registration as the "dipping carriage" is always raised at the end of such a cycle of digitation, the gear 1879 will be moved in a reverse direction by an equal amount, so that the accuracy of movement of the counter is not effected.

It is necessary, when the interposable gear 2000 is engaged with counter gear 1879, to disengage the gear detents 1932 from the gears 1877, in order to permit the train of gears normally connected to gears 1879 to rotate freely. A variety of means can be used to move the detents 1932 to disengaged position, but I prefer to use the mechanism shown in the drawings. This mechanism comprises forming the detents 1932, of which there is one for each order of the counter, with a tail 19320. This tail is engaged by a gate 2040, when the control lever 2020 is moved to the operative or "accumulate" position, by the lowering of the "dipping carriage" bail 269. The gate 2040 is mounted on a pair of bellcrank arms 2041 which are pinned to a shaft 2042 rotatably and longitudinally movable in the side plates 2043 of the machine (Fig. 4). The lower arms of the bellcranks 2041 support a roller 2044 which is positioned immediately below the bail 269. Thus, the dipping of the carriage rocks the bellcranks 2041 (in a counter-clockwise direction in Fig. 1, or clockwise in Fig. 4) whereupon the gate 2040, if the machine is positioned for entry of values from the actuator into the counter register, depresses the tail 19320 of the detents 1932, thereupon releasing the gears 1877 for free rotation.

In view of the fact that the engagement and disengagement of the interposable gear 2000 with the counter gear 1879 causes slight rotation of the latter, it is preferred that the gate 2040 be latched in its lowermost or operative position until the instant the interposable gear 2000 completely disengages the counter gear 1879. This can be secured by a number of means, but a simple and preferred form is shown in Fig. 3. This latch comprises a latching arm 2050 suitably pinned to the machine frame by any suitable means such as pin 2053, and normally urged in a counter-clockwise direction by a spring 2054 tensioned between a stud 2055 on

5 the lever 2050 and a stud 2056 on the machine frame. The upper end of the latch lever 2050 is provided with a shoulder 2051 adapted to engage a stud 2052 mounted on one of the bellcranks 2041. Upon counter-clockwise rotation of the bellcranks 2041 the latching lever 2050 is rocked first clockwise against the tension of its spring 2054 until the pin 2052 has slipped by the shoulder 2051, whereupon the lever is pulled counter-clockwise to latch the bellcranks and their associated gate 2040 in a depressed position.

The lever 2050 is also provided with a projecting shoulder 2057 adapted to be cammed to disengaging position by the last portion of the rise of the dipping bail 269. The shoulder 2057 is formed so that the dipping bail 269 rocks the lever 2050 to disengage its shoulder from the pin 1952 on the instant the interposable gear 2000 becomes disengaged from the counter gear 1879. This permits the counter rotation of the counter gear 1879 caused by the disengagement of the idler gear 2000 to take place freely at the end of digitation. The form of latch shown provides a quick operating latch to disable the detent 1932 as the interposable gear engages counter gear 1879, but provides late unlatching when the carriage is raised.

It is necessary that the detents 1932 be unaffected by the rocking of the bellcranks 2041 in normal operation, but that they all be operated by the gate 2040 when the mechanism is set for accumulation of values in the counter register. This can be secured by several means, but a preferred form is shown in Figs. 4 and 5. As shown in Fig. 5, it is preferred that the gate 2040 be provided with slots 2045 in the lower edge, one positioned adjacent each detent. When the mechanism is positioned for normal operation, in which the counter operates independently of the register, the slot will be positioned as shown in Fig. 5, so that the tails 19320 of the detents will pass through the gate 2040 freely. However, if the shaft 2042 is shifted longitudinally of the carriage, the gate 2040 is likewise shifted, and thereupon the tails 19320 of the detents are engaged by the rocking of the gate 2040.

I propose to shift the shaft 2040 simultaneously with the positioning of the rocker arm 2002 by means of the lever 2020, as is best shown in Fig. 4. Preferably, the left end of the shaft 2042 is provided with a peripheral slot 2060 which embraces the cam end 2061 of lever 2062 which is keyed to spline shaft 2064. The shaft 2064 is rotatably mounted in the carriage end plates 2051, and the lever 2062 is adapted to slide therealong. It will be recalled that the shaft 2042 is mounted in the frame of the machine and the lever 2062 therefore always will be held adjacent the machine frame or side plate 2043, as shown in Fig. 5. However, the control lever 2020 is preferably mounted on the end plate 251 of the carriage, and it is desirable to rock the shaft 2064 from motion of that lever. This can easily be secured by means of a crank arm 2065 mounted at the left end of shaft 2064. A link 2066 is pinned at one end to the control lever 2020, as by means of pin 2022, and at the other end to the crank arm 2065 as by means of pin 2067. Thus, when the control lever 2020 is rocked to its rearward position, counter-clockwise of the position shown in Fig. 4, the arms 2011 are not only rocked to the position shown in Fig. 3, but the lever 2062 is rocked clockwise.

Clockwise rocking of lever 2062 causes the camming arm 2061, which is embraced by the slot 2060, to pull the shaft 2042 to the right in Fig. 5. This positions the gate 2040 so that the tails 1932 of the detents 1932 are engaged by the gate 2040 as it is rocked by the dipping of the carriage.

When the gate 2040 is shifted to the right, as heretofore described, an ear 2070 (see particularly Figs. 1 and 5) formed on the extreme right end thereof moves in front of the nose 18240 of the counter actuator 1824. Thus, the ear 2070 locks forward motion of the actuator 1824 and prevents the nose 18240 from coming into engagement with the counter gear 1880. Such rocking is possible under my construction as the slot 18241 which forms the connection between the counter actuator 1824 and the counter actuator 1830 forms a yielding connection which permits the counter actuator lever 1830 to move through its normal path without moving the counter actuator 1824. It will be recalled that the spring 2075, under normal conditions is sufficiently strong to cause the actuator 1824 to move with the actuator lever 1830 to effect counting in the normal manner.

I claim:

1. In a calculating machine having accumulator wheels, a driving gear for each of said accumulator wheels, actuators for said driving gears, means for engaging said driving gears and said actuators preliminary to digitation and for disengaging the same subsequent thereto, counter wheels, a driving gear for each of said counter wheels, and an actuator for said counter wheel driving gears; the combination which comprises interposable gears engaging said accumulator wheel driving gears and normally disengaged from said counter wheel driving gears, means for rendering said counter actuator inoperative to move said counter wheels, and a manually operated control means operative to position said interposable gears so they engage said counter wheel driving gears upon engagement of said accumulator driving wheels with their respective actuators and to render inoperative said counter actuator.

2. In a calculating machine having accumulator wheels, a driving gear for driving each of said accumulator wheels, crawl tens-transfer devices between said accumulator wheels, actuating gears for differentially rotating said accumulator wheel driving gears, means for operatively engaging said accumulator wheel driving gears with said actuator gears preliminary to digitation and for disconnecting the same subsequent to digitation, counting wheels, a gear for driving each of said counting wheels, crawl tens-transfer devices between said counting wheels, and a counter actuator; the combination which comprises a pivotally mounted lever associated with each accumulator wheel, an interposable gear mounted on each said lever engaging the accumulator wheel driving gear, said lever being positionable to engage said interposable gear with said counter wheel driving gear upon engagement of said accumulator wheel driving gears with said actuator gears, means for rendering said counter actuator inoperative to move said counter wheels, and a manually operated control means operative to position said levers to cause said interposable gears to engage said counter wheel driving gears and to simultaneously render said counter actuator inoperative with respect to said counter gears.

3. In a calculating machine having a frame, a carriage shiftable laterally on said frame, an ordinarily arranged accumulator register in said carriage, actuating means for said accumulator register mounted on said frame, means for rocking the carriage to engage said accumulator register with the actuating means prior to digitation and to rock it out of such engagement subsequent to digitation, an ordinarily arranged counter register in said carriage, an counter operating means mounted on said frame for operating said counter register; the combination which comprises positionable means for operatively connecting each order of the said counter register to the corresponding order of said accumulator register, means for positioning said positionable means in connecting relationship to said register throughout the period of engagement of the accumulator register and the actuating means, and means operative simultaneously with said positionable means for rendering said counter operating means inoperative to move said counter register.

4. In a calculating machine having an ordinarily arranged accumulator register, actuating means for said accumulator register, means for rocking the accumulator register into engagement with the actuating means prior to digitation and to rock it out of such engagement subsequent to digitation, an ordinarily arranged counter, and counting means for operating said counter; the combination which comprises normally inoperative gearing positionable to connect each order of the said counter to the corresponding order of said accumulator register, means for positioning such gearing, means for holding said gearing in connecting position throughout the period during which the accumulator register is rocked into engagement with said actuating means, and means operative simultaneously with said gearing positioning means for rendering said counting means inoperative to move said counter.

5. In a calculating machine having a frame, a carriage shiftable laterally on said frame, an ordinarily arranged accumulator register mounted in said carriage, actuating gears mounted on said frame for driving said accumulator register, means for rocking the carriage to engage the accumulator register with the actuating gears prior to digitation and to restore the carriage to its disengaged position subsequent to digitation, an ordinarily arranged counter register in said carriage, and counting means mounted on said frame for operating said counter register; the combination which comprises interposable gearing between said accumulator register and said counter register, said gearing having a normal disconnecting position and a connecting position with respect to said registers, manually operated means for determining the position of said interposable gearing, means controlled by said manually operated means for disabling said counting means when said interposable gearing is in connecting position, and holding means effective to retain said interposable gearing in either adjusted position while the carriage is in its rocked position.

6. In a calculating machine having an ordinarily arranged accumulator register, a crawl type tens-transfer device between the various orders of the accumulator register, an actuator for said accumulator register, an ordinarily arranged counter register, the corresponding orders of said registers being in the same planes, counting means for said counter register, and a crawl type tens-

transfer device between the various orders of the counter register: the combination which comprises a normally disengaged connecting gearing for driving said counter register from said actuator, means for rendering said counting means inoperative to move said counter register, a manually operated control means operative to position said normally disengaged connecting gearing into engaging position and to operate said means for rendering said counting means inoperative, and means for retaining said connecting gearing in engaging position throughout operation of said accumulator actuator.

7. In a calculating machine having accumulator gears, actuating means for said accumulator gears, counter gears, a counter actuating means for said counter gears, means for engaging said accumulator gears and said actuating means preliminary to digitation and for disengaging the same subsequent thereto: the combination which comprises interposable gears for selectively connecting said counter gears to said accumulator gears, means for rendering said counter actuating means inoperative to move said counter gears, a manually positionable member, and means jointly under the control of said member and said means for engaging said accumulator gears and said actuating means for positioning said interposable gears to connect said counter gears and said accumulator gears and to operate said means for rendering said counter actuating means inoperative.

8. In a calculating machine having accumulator dials, tens-transfer devices between said accumulator dials, actuating means for said accumulator dials, engaging means operable to operatively connect said dials with said actuating means preliminary to digitation and for disengaging the same subsequent thereto, counter dials, tens-transfer devices between said counter dials, and counter operating means for said counter dials: the combination which comprises interposable gears positionable to connect said counter dials to said actuating means, means operable by said engaging means for positioning said interposable gears in connecting relationship, and control means for selectively conditioning said interposable gears to be positioned in connecting relationship by operation of said engaging means to engaging position and to be positioned in disconnecting relationship by the subsequent disengagement of said engaging means and for rendering said counter operating means inoperative to move said counter dials.

9. In a calculating machine having accumulator wheels, crawl type tens-transfer devices between said accumulator wheels, actuating means for said accumulator wheels normally disconnected therefrom, means for connecting said accumulator wheels and said actuating means preliminary to digitation and for disengaging the same subsequent thereto, counter wheels, crawl type tens-transfer devices between said counter wheels, and actuating means for said counter wheels: the combination which comprises means including gears positionable to operatively connect said counter wheels to said accumulator wheels, means for simultaneously positioning said gears in connecting relationship and for rendering said counter actuating means inoperative to move said counter wheels, and means for holding said positionable gears in such connecting relationship throughout the period of engagement of said accumulator wheels by said accumulator actuating means.

10. In a calculating machine having accumulator wheels, normally disconnected actuators for said accumulator wheels, engaging means operable to operatively connect said accumulator wheels with said actuators during digitation, counter wheels, and an actuator for said counter wheels: the combination which comprises a normally disengaged connecting means for driving said counter wheels from said accumulator wheels, means for rendering said counter actuator inoperative to move said counter wheels, a manually operated control means including means operative to operate said means for rendering said counter actuator inoperative, and means jointly operable by said manually operated control means and by said engaging means for positioning said connecting means into connecting relationship with said accumulator wheels and said counter wheels.

11. In a calculating machine having accumulator wheels, normally disconnected actuators for said accumulator wheels, engaging means operable to operatively connect said accumulator wheels with said actuators during digitation, counter wheels, an actuator for said counter wheels, crawl tens-transfer devices between the various orders of said accumulator wheels, crawl tens-transfer devices between the various orders of said counter wheels, and aligning means for said accumulator wheels and said counter wheels to eliminate partial transfers: the combination which comprises a normally disengaged gearing for driving said counter wheels from said accumulator wheels, means operable by said engaging means for positioning said gearing into operative relationship with said accumulator wheels and said counter wheels if said gearing is in a preselected position; means for rendering said counter actuator inoperative to move said counter wheels, and a manually positioned control means operative to move said gearing into the preselected position and to operate said means for rendering said counter actuator inoperative.

12. In a calculating machine comprising accumulator wheels connected by entrained gearing and mechanism including cams operable by said accumulator wheels for controlling the alignment of said numeral wheels, counter wheels connected by entrained gearing and mechanism including cams operable by said counter wheels for controlling the alignment of said counter wheels, actuating means for said accumulator wheels, means for engaging said accumulator wheels with said actuating means preliminary to digitation and for disengaging the same subsequent thereto, and a counting means for said counter wheels; the improvement which comprises means including interposable gears positionable to connect said counter wheels with said accumulator wheels during engagement of said accumulator wheels and said actuating means, and control means for positioning said interposable gears in connecting position and for rendering said counting means inoperative to move said counter wheels.

GRANT C. ELLERBECK.
